UNITED STATES PATENT OFFICE

FRANZ HALSTRUP, OF FREIBURG, IM BREISGAU, GERMANY, ASSIGNOR TO SCHWARZ-WÄLDER LAMPENUHRENFABRIK G. M. B. H. GLÖBURA, OF FREIBURG, IM BREISGAU, GERMANY

CLOCK

Application filed October 19, 1926, Serial No. 142,570, and in Germany April 26, 1926.

The present invention has reference to improvements in clocks and relates more specifically to an alarm clock in which the horary and minute dials are represented by 5 clock work operated semi-spherical glass bowls which together form a hollow translucent globe to be automatically illuminated from within upon the alarm unit coming into action. Means are provided for actuating 10 or arresting the alarm mechanism or striking works and the lighting mechanism independently of one another or in timed coaction.

In order to make my invention readily understood I will describe the several novel and improved features in detail in connection with the accompanying drawings, in which Fig. 1 is a vertical median section through the clock, the conventional clock and 15 alarm works and the electric battery not being shown for the sake of clearness; Fig. 1^a shows a fragmentary view, partly in section, of the minute tube in extended state; Fig. 2 is a plan view of the clock base with 20 the works proper removed; Fig. 3 is a cross-section on line 3—3 of Fig. 1; Fig. 4 is a section through an hour tube and alarm detail; Fig. 5 is a plan view of the works with the lighting unit in "cut-in" position; Fig. 6 is a 25 similar view with the parts in the normal, that is to say "cut-out" position; Fig. 7 is the same view, but with the releasing lever temporarily held out of coaction with the ratchet wheel for preventing illumination 30 during the striking of the alarm. Fig. 8 is a view of the works from below; Fig. 9 a cross-section on line 9—9 of Fig. 6; and Fig. 10 shows the horary and minute annuli and adjacent parts.

To the clock housing 2 is rigidly secured 35 the single hand 3, from which extends inwardly the pointer 63 for setting the alarm unit. The upper portion 4 of the clock hand, which curves over the upper hemisphere 10, can readily be detached from the lower portion 45 for assembling or disassembling purposes. The hour tube 5 supports at its upper end the hour glass bowl 6 and surrounds the minute tube 7 from the upper end of which latter extend the bracket arms 8, which

jointly support the minute annulus 9 of the inverted minute glass bowl 10.

On the upper bearing 112 (Fig. 1^a) of the minute arbor 12 is mounted the double-armed switch lever 11, which can be oscillated sideways by means of the bell-crank 15 (Fig. 9), which latter is rockingly mounted on the shaft 13 of the push button 14. For this purpose the one end of the lever 11 is laterally enlarged and the two end portions are turned 60 up to form contact cheeks 16 and 17 respectively (Figs. 5 and 9). From the other end of the lever 11 depends the insulated metal contact roller 18, designed to electrically connect the two contact terminals 65 23 and 24 in the clock base (Fig. 1). A stud 30 upstanding from the lever 11 can coact respectively with the crimps 19 and 20 of the snap spring 21 (Figs. 5 and 6) for temporarily locking the lever 11 in its ad- 70 justed position.

On the switch lever 11 is fulcrumed the bell-crank releaser 25, 26 which is influenced by the spring 27 in such manner that its one extremity 26 is always pressed against the 75 eccentric 28. Its other, free, end 25 cooperates in the "cut-out" position (Fig. 6) with the ratchet wheel 34 fast on the alarm winding stem 22. On the operation of the alarm the lever 11 is moved over into the position 80 shown in Fig. 5, in which the contact roller 18 electrically connects the two contact springs 23 and 24 for switching-in the light 46 within the glass globe.

The lever 25, 26 is mounted on the switch 85 lever 11 by means of slot movement 29 to insure proper operative engagement of the lever end 25 in the ratchet wheel 34 at all relative positions of the latter.

In the upper plate 1 is provided a cut-out 90 31 (Figs. 5 to 7) for allowing the spring-influenced angle lever 32 to freely pass therethrough for the purpose of locking the alarm anchor 62 by means of the bent arrester 35 extending from the rock shaft 33 (Fig. 9). If 95 the lever 32 is moved in the direction of the arrows (Fig. 9), the alarm can sound. At the same time the arm 35 also serves for automatically arresting the alarm action, for after the alarm spring has expanded to a certain 100

extent it will contact with the arrester arm 35 and stop its further movement.

The shaft 13 of the push button 14 carries at its lower end a laterally extending pin 36 which, upon the button being rotated in the direction of the arrow (Fig. 8), contacts with the bell crank 37 and causes the latter to engage in the teeth of the alarm wheel 38 and thereby stops the alarm action. On winding up the alarm spring the alarm wheel 38 moves backward to a small extent which allows the lever 37, urged by the spring 39, to move back again into the dotted line position 37^a, releasing thereby the wheel 38.

40 denotes the alarm setting annulus (Figs. 1, 4 and 10) in which is mounted internally the small ring 42 presenting a notch 41 (Fig. 4). Upon this ring 42 slides a pin 43 rigidly extending from the hour tube 5 and definitely signed to carry the entire weight of the hour bowl 6. This pin 43 at the set time drops into the notch 41, which movement frees the angle lever 32 whose upper end slides on the hour wheel 44, so that the lever 32 can rock in the arrow-indicated direction (Fig. 9), releasing thereby the arm 35 and in turn the alarm action.

To the upper end of the spindle 147 of the setting knob 47 (Fig. 1) is fixed the eccentric 39 which coacts with the releaser lever 25, 26, as shown in Figs. 5 to 7, for rocking it, if desired, out of contact with the alarm ratchet wheel 34, so that then the light will not be switched-in during the alarm action.

35 The minute arbor 12 (Fig. 1^a) is coupled to the minute tube 7 by means of a ball joint 49, whose lateral pin 50 engages in a notch 150 of the coupling sleeve 61. This coupling is designed to allow of independent movement of the two complementary shafts within limits.

The minute tube 7 houses insulatedly the current conducting tube 57 which carries at its lower end the contact annulus 64. Within 45 this tube 57 is arranged, insulated by the member 60, a current conducting rod 56, to the lower end of which is secured the coupling sleeve 61 which serves as second current conductor. 58 is a step bearing for supporting 50 the weight of the minute arbor 12, the minute tube 7 and the minute glass 10.

The operation of the described mechanisms is as follows:—

In the normal position of the parts (Fig. 55 6) in which the light is "off", the arm 25 of the releaser lever engages in the teeth of the ratchet wheel 34. If now the alarm sounds at the set time the wheel 34 will rock the switch lever 11 into the position of Fig. 5 through 60 forcing back of the lever arm 25, when the contact roller 18 connects the two contact springs 23 and 24, which automatically cuts in the lamp 46.

In the summer time with its early daylight, 65 when it is not necessary to cut-in the artificial

light on the sounding of the alarm, it suffices to turn the bottom knob 47, which correspondingly rotates the top eccentric 28 to allow the releaser lever 25, 26 to move out of contact with the ratchet wheel 34 (Fig. 7). The switch lever 11 can be actuated at any time independently of the alarm mechanism by the push button 14, since the rocking lever 15 (Fig. 9) on descent with the push button rod 13 presses with its one arm against the upturned edge 16 of the lever 11 forcing the latter aside. The other arm of the lever 15 during this down-movement enters the slot 48 in the plate 1. On return of the push button, under the influence of the spring 55, a leaf spring 52 so actuates the rocking lever 15 that the free lever arm comes into contact with the other upturned lever edge 17. On renewed depression of the push button the lever 15 will then return the switch lever 11 into the initial position.

On each rocking displacement of the switch lever 11 the contact roller will connect or disconnect, as the case may be, the two contact terminals 23 and 24. From these latter the electric current is transmitted by means of the permanently contacting wiper springs 53 and 54 to the insulated current conducting members 56 and 57 within the minute tube 7, as above described.

95 The alarm is set on the dial annulus 40 arranged below the hour glass 6 and provided with a graduated hour scale. As stated above, this annulus carries the notched ring 42 upon which loosely rests the concentrically extending hour tube 5 by its pin 43. Upon rotation of the hour tube in the direction of the arrow b in Fig. 4, the pin 43 at the set time will drop into the notch 41 of ring 42, when by this axial displacement of 100 the tube 5 the angle lever 32 will be rocked in the direction of the arrow in Fig. 9, since it extends with its one extremity into the 105 domain of the hour wheel 44 fast on the hour tube 5, which frees the arm 35 of the alarm arbor 33, allowing the alarm to function.

110 For arresting the alarm it is only necessary to turn the push button 14, when its lower lateral pin 26 will so act on the bell crank 37 that it engages in the alarm wheel 38 to lock the latter (Fig. 8). On return of the push button into the normal position, the spring 39 urges the lever 37 away from the wheel 38.

115 By means of the described mechanisms it will be seen that on setting-off of the alarm simultaneously the light is switched-on, so that the user does not have to search around in the dark for the light switch. He can also, if desired, temporarily disconnect the lighting unit from the alarm unit. Since all current conducting parts are mounted on the 120 casing, the clock work proper can readily be removed for repairing purposes without re- 125 130

quiring the watchmaker to disconnect or remove any electrical part or parts.

Dry battery or house current may be used for lighting the clock.

5. What I claim is:—

1. In a switch mechanism, a switch lever movable to positions for opening and closing a circuit, means including an element mounted on the lever and operable when in a predetermined working position for shifting said lever from circuit opening to circuit closing position, a member movable to shift said element out of such predetermined position, and means independent of the first-named 10 means for shifting the lever to circuit opening and closing positions.

2. In a switch mechanism, a circuit opening and closing switch lever, an actuating lever fulcrumed on the switch lever, means 20 for operating the same for imparting circuit closing movement to the switch lever, a locking member for locking said means from action, and means for releasing said locking member.

25. 3. In a switch mechanism, a two-armed switch lever movable to positions for opening and closing a circuit, a two-armed actuating lever pivotally mounted on one of the arms of the switch lever, operating means connected with the other arm of the switch lever, operating means acting on one of the arms of the actuating lever for shifting the switch lever to one position, and means acting on the other arm of said actuating lever to shift 30 the first-named arm of said lever to a position in which it is rendered inoperable by 35 the second-named operating means.

4. In a switch mechanism, a two-armed switch lever movable to positions for opening and closing a circuit, a spring-controlled 40 bell crank actuating lever pivotally mounted on one of the arms of the switch lever, operating means connected with the other arm of the switch lever, operating means 45 acting on one of the arms of the actuating lever for shifting the switch lever to one position, and means acting on the other arm of said actuating lever to shift the first-named arm of said lever to a position in which it is 50 rendered inoperable by the second-named operating means.

5. In a switch mechanism, a switch lever movable to positions for opening and closing a circuit, an actuating lever pivotally mounted on said switch lever, operative 55 means directly acting on the switch lever for shifting it to either circuit opening or circuit closing positions, operative means acting on the actuating lever when said actuating lever is in a predetermined position for shifting the switch lever to one of said positions, locking means for holding the second-named operative means inoperative, means 60 operable by the first-named operative means 65 without affecting the switch lever for releas-

ing said locking means, and means operable on the actuating lever for rendering it inoperative by the second-named operative means.

In testimony whereof I affix my signature. 70
FRANZ HALSTRUP.
